UNITED STATES PATENT OFFICE.

HENRY H. SWIFT, OF HART'S VILLAGE, NEW YORK.

IMPROVED MODE OF ATTACHING CHIMNEYS TO LAMPS.

Specification forming part of Letters Patent No. 37,366, dated January 6, 1863.

To all whom it may concern:

Be it known that I, HENRY H. SWIFT, of Hart's Village, in the county of Dutchess and State of New York, have invented a new and Improved Mode of Attaching Chimneys to Lamp-Burners; and I do hereby declare that the following is a full, clear, and exact description of the same, reference being had to the accompanying drawings, making a part of this specification, in which—

Figure 1 is a vertical section of a lamp-burner with my invention applied to it; Fig. 2, a plan or top view of the same.

Similar letters of reference indicate corresponding parts in the two figures.

The object of this invention is to obtain a simple and efficient fastening for securing chimneys to lamp-burners, one which will yield or give as the chimney expands under the heat from the flame, so as to prevent the chimney from fracturing, and one also which will admit of the chimney being readily adjusted to the burner and detached therefrom.

To enable those skilled in the art to fully understand and construct my invention, I will proceed to describe it.

A represents a lamp-burner, which may be constructed in the ordinary way, B being the wick-tube; C the cone or deflector, and D the flange within which the base of the chimney is fitted.

E is a spring constructed of a thin plate of

any suitable metal, and bent in bow form, as shown clearly in Fig. 2. This spring passes horizontally through holes or openings a a in the flange D, and has its ends permanently secured to the flange at points b b, which are opposite to the holes or openings a a, as shown clearly in Fig. 2. This spring E is of such a form that its sides c c within the flange D will catch over the flange at the base of the chimney and retain it firmly on the burner, and by pressing the outer part of the spring E inward or toward the burner the sides c c will be forced outward and from the flange of the chimney, as shown in red in Fig. 2, thereby releasing the chimney, so that it may be removed from the burner. The sides c c of the spring E are to be sufficiently elastic to yield or give under the expansion of the chimney, so as to prevent the fracture of the same from that cause.

The device, it will be seen, may be applied at a small cost.

Having thus described my invention, what I claim as new, and desire to secure by Letters Patent, is—

The spring E, bent or curved in bow form and applied to the burner A, substantially as and for the purpose herein set forth.

HENRY H. SWIFT.
